VIBRATORY SHAKER FOR UNLOADING RAIL- ROAD CARS OR THE LIKE

Edwin F. Peterson, % Martin Engineering Company,
Neponset, Ill.

Filed May 4, 1960, Ser. No. 60,447

Term of patent 14 years

(Cl. D55—1)

FIG. 1

FIG. 4

FIG. 2

FIG. 3

FIG. 1 is a perspective view showing a vibratory shaker for unloading railroad cars or the like, illustrating the top and one side and end;

FIG. 2 is a perspective view thereof, illustrating the top and the side and end opposite those shown in FIG. 1;

FIG. 3 is a perspective view thereof, illustrating the top, same side and opposite end from that shown in FIG. 2; and

FIG. 4 is an elevational view of the side shown in FIG. 1.

I claim:

The ornamental design for a vibratory shaker for unloading railroad cars or the like, substantially as shown.
